UNITED STATES PATENT OFFICE

2,613,950

FOLDING WHEELED CARRIER FOR
SUITCASES

Eleanor P. Bartlett, Dover-Foxcroft, Maine

Application August 6, 1948, Serial No. 42,921

7 Claims. (Cl. 280—35)

1

This invention relates to new and useful improvements in wheeled carriages and the primary object of the present invention is to provide an attachment for suitcases, baggages and the like, that will facilitate a convenient wheeled action of the article on which the same is applied.

Another important object of the invention is to provide an attachment for suitcases including a novel and improved wheel frame that will support the suitcase in a position for movement and which is quickly and readily applied to or removed from the suitcase in a convenient manner.

Yet another important object of the present invention is to provide a novel and improved handle construction that is quickly and readily applied in position to a suitcase and which is adjustable to accommodate persons having arm lengths of various sizes.

A further object of the present invention is to provide an attachment for suitcases and the like including a wheeled frame, and a handle structure, which is mountable on a suitcase at a selected point thereon to be used in moving or transporting the suitcase and which is positionable relative to the wheeled frame to retain the said suitcase in a supported and elevated position against movement in which instance the handle construction would function as a further support for the suitcase.

A still further aim of the present invention is to provide an attachment for suitcases that is simple and practical in construction, strong and reliable in use, neat and attractive in appearance, small and compact in structure, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of a suitcase and showing the present invention applied thereto for use in wheeling the said suitcase;

Figure 2 is a longitudinal vertical sectional view taken substantially through the center of the handle structure used in conjunction with the present invention;

Figure 3 is a transverse vertical sectional view taken substantially on the plane of section line 3—3 of Figure 2;

Figure 4 is a fragmentary, horizontal trans-

verse sectional view taken substantially on the plane of section line 4—4 of Figure 2;

Figure 5 is a perspective view of the wheeled frame used in conjunction with the present invention;

Figure 6 is a longitudinal horizontal sectional view taken substantially on the plane of section line 6—6 of Figure 5;

Figure 7 is a fragmentary perspective view of one portion of the suitcase used in conjunction with the present invention;

Figure 8 is a longitudinal vertical sectional view taken substantially on the plane of section line 8—8 of Figure 7;

Figure 9 is a perspective view of the wheeled frame used in conjunction with the present invention, in slightly modified form; and

Figure 10 is a group perspective view of the handle supporting means used in conjunction with the present invention, in slightly modified form.

Referring now to the drawings in detail, wherein for the purpose of illustration, there is disclosed a preferred embodiment of the present invention, the numeral 10 represents the handle structure of the present invention generally, including a pair of substantially rectangular inner and outer sections or members 12 and 14.

A plurality of longitudinally spaced guide pins 16 are fixed to the inner section 12 and project outwardly therefrom to slidably engage a longitudinal slot 18 provided in the outer section 14.

In order to normally urge these sections 12 and 14 inwardly relative to each other, there is provided an elongated resilient member or coil spring 20 the ends of which are anchored to holding pins 22, 24 and are fixed to the respective sections 12 and 14.

Suitably secured by adhesive means or the like to the inner face of the section 12, is a pair of substantially rectangular strips of resilient material 26 having serrated or toothed bearing surfaces 28.

The outer end of the section 12 is notched and apertured at 32 to pivotally engage the reduced arcuate end portions 34 of a side member or section 36 and the outer end of the section 14 is also notched as at 38 and apertured as at 40 to pivotally engage the reduced arcuate end 42 of a further side member or section 44.

Fixed to the inner faces of the side sections 36 and 44, by rivets or the like 46, or holding plates 48 to which there are fixed resilient pads 50 preferably formed with toothed or serrated bearing surfaces 52. These rivets 46 are provided with

substantially rectangular head portions 54 that slidably engage longitudinal slots 56 provided in a pair of side elements or straps 58.

Further guide pins 60 are also fixed to the side sections 36 and 44 and engage these slots 56 to permit only longitudinal movement of the straps relative to the side sections 36 and 44.

Threaded studs integral with the heads or guides 54 receivably engage wing nuts 62 which are adjustable to bear against the straps 58 in order to adjustably retain the straps 58 in a selected extended position relative to the side sections 36 and 44.

An auxiliary, substantially channel shaped guide 64 is fixed to the side section 36 and slidably receives and supports the longitudinal movement of the strap 58 relative to the said side section 36.

A pair of slidably engaged concavely convexed hand gripping sections 66 and 68 are provided with reduced arcuate or looped outer terminals 70 that engage notches 72 in the upper ends of the straps 58 and openings or apertures 74 adjacent the upper ends of the straps 58, for pivotal movement of the straps 58 relative to the hand grips 66 and 68.

To prevent disengagement of the hand grips 66 and 68 from each other, there is provided a pair of detents or lugs 76 which are integral with one of the grips and which bear against the remaining grip.

A transverse bar 78 is fixed by welding or the like to the central portion of the inner section 12, between the pads or strips 26, and includes outwardly projecting terminal hooks 80 that will engage headed bolts or fasteners 82 that are removably carried by one end wall 84 of a suitcase or baggage 86.

Reference is now directed to Figures 5 and 6, wherein there is disclosed the wheeled frame portion of the present invention, which is designated generally by the numeral 88. This wheeled frame 88 includes inner and outer sections 90 and 92 one of which, for example section 90 supports a plurality of guide pins 94 that slidably engage a guide opening or slot 96 provided in the remaining section, namely, section 92.

Pins 98 and 100 project from the section 90 and 92 to engage the ends of an elongated, resilient member or coil spring one of two that urges the sections 90 and 92 inwardly toward each other.

A pair of longitudinally spaced resilient pads 104 having serrated or toothed bearing surfaces are suitably fixed to the inner section 90 and a transverse anchor plate 106 is rigidly attached to the central portion of the inner section 90 and includes terminal hooks 108 that engage headed bolts (similar to 82) which are removably secured to the suitcase 86 with the pads 104 bearing against the said suitcase.

Laterally projecting arms 110 and 112 are integrally formed with the inner and outer sections 90 and 92 respectively, and are notched as at 114 to pivotally engage the reduced ends 116 of a pair of holding members 118.

Bearing pads 120 are fixed in any suitable manner to the members 118 and bear against the outer surface of the suitcase 86, as shown best in Figure 1 of the drawings.

Transverse slots 122 are provided adjacent the outer ends of the sections 90 and 92, and the slots 122 pivotally engage the reduced ends 124 of a pair of side sections or members 126 which support stub axles 128 for rubber tired wheels 130.

Plates 132 are fixed to the side members 126 75

and support resilient pads 134 having toothed or serrated bearing surfaces that will engage the outer surface of the suitcase 86.

In practical use of the present invention, the side sections 36 and 44 of the handle structure 10 are pulled outwardly away from each other and placed on opposite sides of the suitcase 86. The spring 20 will urge the said side sections 36 and 44 inwardly to bear against the outer faces of the suitcase 86, and the terminal hooks 80 are engaged with the fasteners 82 to prevent movement of the handle structure 10 relative to the suitcase. The wing nuts 62 are tightened when the hand grips 66 and 68 are disposed at a selected extended position relative to the sections 12 and 14.

The side sections or members 126 of the wheeled frame 88 are also pulled outwardly away from each other and are disposed on opposite sides of the suitcase 86, and diagonally from the handle structure 10 with the bearing elements 120 engaging the lower face of the suitcase 86, as shown best in Figure 1 of the drawings. The terminal hooks 108 of the anchor plate 106 are engaged with suitable fasteners 82 (not shown) which are secured to the normally lower or bottom wall of the suitcase 86.

It should be noted that the handle structure 10 may be placed in a selective position on the suitcase 86, so that the hand grips 66 and 68 may cooperate with the wheeled frame 88 to support the suitcase 86 in an upright, substantially vertical position and raised above the ground surface or floor surface on which the wheels 130 and grips 66 and 68 bear.

Reference is now directed to Figure 9, wherein there is disclosed the wheel supporting frame in slightly modified form. In this embodiment, an angle member 136 is rigidly secured or removably secured by rivets, fasteners or the like to the lower corners of the suitcase 86. Stub axles 138 will project outwardly from the angle members 136 to support a suitable wheel similar to that disclosed by the numeral 130.

Figure 10 illustrates a modified embodiment of the handle supporting frame that will replace the inner and outer sections 10 and 12 and the side sections 36 and 44 pivotally secured thereto. This handle supporting element or handle member 140 is provided with a pair of integral guides or L-shaped brackets 142 that will slidably engage the straps 58. Projecting outwardly from the member 140, is an externally threaded rod or bolt 144 that receives the guide slots 56 provided in the straps 58. A holding nut 146 and washer 148 are received on the bolt 144 and bear against the outer surface of the straps 58 to retain the said straps in a longitudinally adjusted position relative to the member or members 140.

It is obvious that the members shown in Figures 9 and 10 of the drawings are employed when it is desirable to manufacture a suitcase having a wheeled frame and handle structure permanently applied thereto. However, the said members 136 and 140 may be removably secured to a suitcase by merely inserting fasteners or the like through openings or apertures which are suitably provided in the said members.

Although illustrated in the drawings, the handle structure 10 is composed of sections which are hinged or pivoted together in a particular manner, it is obvious that the same could be so connected to each other as to permit the said handle construction to be completely collapsed, for shipment, transport or the like.

The above is likewise true for the heeled frame 88 and it is obvious that the end sections 126 thereof may be folded inwardly upon the inner section 90 as well as the folding members 118 to permit the said device to be collapsed into a relatively small article for shipment or storage.

It should be noted that the present wheeled frame 88 and handle construction 10 may be applied to other articles other than suitcases, such as boxes, baggages, containers or the like in which instance it would not be necessary to employ the anchoring members or fasteners 82.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A suitcase attachment, said attachment comprising a wheeled frame removably secured to said suitcase, said wheeled frame including inner and outer sections slidably connected together, an end section hinged to each of said inner and outer sections, a pressure member carried by each of said end sections, means urging said inner and outer sections inwardly toward each other for clamping said pressure members against the sides of a suitcase, means for anchoring said inner section to a suitcase, stub axles carried by said end sections below said pressure members, and wheels mounted on said stub axles, said inner and outer sections including lateral projections, and hinged pressure elements carried by said lateral projections.

2. A suitcase attachment comprising a pair of elongated juxtaposed plates, said plates being disposed one above the other and including outer end portions, means slidably securing said plates together, means connecting said plates and yieldingly urging the outer ends of said plates toward each other, a pair of vertically swingable outer arms pivoted to the outer end portions of said plates, pressure members mounted on said arms, stub axles projecting laterally from said arms and paralleling the plates when the arms are disposed perpendicular to the plates, a wheel on each stub axle, an anchor plate attached to one of said plates and overlying said pair of plates, a horizontal arm projecting laterally from each of said pair of plates, and pressure members pivoted to said horizontal arms for vertical swinging movement.

3. A suitcase attachment comprising a pair of elongated juxtaposed plates, said plates being disposed one above the other and including outer end portions, means slidably securing said plates together, means connecting said plates and yieldingly urging the outer ends of said plates toward each other, a pair of vertically swingable outer arms pivoted to the outer end portions of said plates, pressure members mounted on said arms, stub axles projecting laterally from said arms and paralleling the plates when the arms are disposed perpendicular to the plates, a wheel on each stub axle, an anchor plate attached to one of said plates and overlying said

pair of plates, a horizontal arm projecting laterally from each of said pair of plates, and pressure members pivoted to said horizontal arms for vertical swinging movement, said connecting means including an elongated spring member underlying said pair of plates and terminally secured to the outer end portions of said pair of plates.

4. A suitcase attachment comprising a pair of elongated juxtaposed plates, said plates being disposed one above the other and including outer end portions, means slidably securing said plates together, means connecting said plates and yieldingly urging the outer ends of said plates toward each other, a pair of vertically swingable outer arms pivoted to the outer end portions of said plates, pressure members mounted on said arms, stub axles projecting laterally from said arms and paralleling the plates when the arms are disposed perpendicular to the plates, a wheel on each stub axle, an anchor plate attached to one of said plates and overlying said pair of plates, a horizontal arm projecting laterally from each of said pair of plates, and pressure members pivoted to said horizontal arms for vertical swinging movement, said connecting means including an elongated spring member underlying said pair of plates and terminally secured to the outer end portions of said pair of plates.

5. An attachment for suitcases and the like comprising a pair of elongated upper and lower flat plates having outer end portions, said lower plate having an elongated guide slot therein, a pair of guide pins depending from the upper plate and slidably received in said slot, a pair of arms attached to the outer end portions of said plates, stub axles projecting outwardly from said arms, wheels on said stub axles, pressure pads on the arms, spring means yieldingly urging the arms toward each other to grip a structure between the pads, and a pair of substantially L-shaped members carried by said plates and cooperating with said arms for retaining a structure on said plates, said L-shaped members including horizontal legs fixed to and disposed at right angles to said arms, vertically swingable legs and hinge means joining said horizontal legs to said swingable legs.

6. An attachment for suitcases and the like comprising a pair of elongated upper and lower flat plates having outer end portions, said lower plate having an elongated guide slot therein, a pair of guide pins depending from the upper plate and slidably received in said slot, a pair of arms attached to the outer end portions of said plates, stub axles projecting outwardly from said arms, wheels on said stub axles, pressure pads on the arms, spring means yieldingly urging the arms toward each other to grip a structure between the pads, and a pair of substantially L-shaped members carried by said plates and cooperating with said arms for retaining a structure on said plates, said L-shaped members including horizontal portions rigidly attached to said plates and projecting laterally from said plates, said L-shaped members also including outer sections pivotally secured to said horizontal portions and swingable vertically toward and away from said plates.

7. A collapsible wheeled support for suitcases and the like comprising a pair of elongated and flat upper and lower juxtaposed slidably connected plates having outer end portions, a pair of vertically swingable end members hinged to the outer end portions of said plates, pressure pads carried by the end members, stub axles pro-

jecting laterally from the outer faces of said end members and paralleling said plates when the end members are disposed perpendicular to the plates, wheels on said axles, a horizontal arm fixed to and projecting laterally from each plate, a pressure element hinged to each arm for vertical swinging movement, spring means underlying the plates and connected to the outer end portions of said plates for yieldingly urging the end members toward each other, and an anchor plate disposed transversely of said plates and having terminal hooks overhanging said plates.

ELEANOR P. BARTLETT.
